CATHODE RAY TUBE APPARATUS

Waldemar J. Poch, Collingswood, N. J., assignor
to Radio Corporation of America, a corporation
of Delaware

Application December 30, 1938, Serial No. 248,570

4 Claims. (Cl. 250—27)

My invention relates to cathode ray tube apparatus and particularly to protective and/or blanking circuits for cathode ray tubes in a television system.

The invention will be described with respect to a television transmitter of the type which utilizes a cathode ray pickup tube or iconoscope. In transmitters of this type, it is desirable to block the cathode ray during the horizontal return line period and during the vertical return period while the iconoscope mosaic screen is being scanned. It is also desirable to provide protective means for the purpose of avoiding damage to the mosaic screen in the event of failure of the cathode ray deflecting means.

It is accordingly an object of my invention to provide an improved circuit for blanking or blocking a cathode ray during the return period following its useful deflecting period.

It is a further object of my invention to provide an improved protective circuit for a cathode ray tube.

It is a further object of my invention to provide an improved circuit which functions both as a cathode ray tube protective means and as a return line blanking means.

The invention will be better understood from the following description taken in connection with the accompanying drawings in which—

Figure 1 is a circuit diagram of a preferred embodiment of my invention.

Figures 2, 3 and 4 are curves which are referred to in explaining the invention, and

Figure 5 is a diagram showing the action of one of the amplifier tubes in Figure 1.

Referring to Fig. 1, my invention is shown applied to a television transmitter comprising a cathode ray pickup tube 1 of the type known as the iconoscope. The tube 1 comprises a highly evacuated envelope having therein an indirectly heated cathode 2, a control electrode 3, a first anode 4, a second anode 6 and a mosaic screen 7 upon which there is projected the picture to be transmitted. The screen 7 in its most common form is made up of a large number of minute photoelectric or capacity elements which are insulated from each other and from a metallic signal plate 8.

The cathode ray is caused to scan the screen 7 by means of deflecting coils 11 and 12 which deflect the ray horizontally and vertically, respectively. Saw-tooth deflection is employed, saw-tooth current, which recurs at a comparatively high frequency, being forced through the coils 11 by means of a horizontal deflecting circuit 13, and

saw-tooth current, which recurs at a comparatively low frequency, being forced through the coils 12 by means of a vertical deflecting circuit 14.

As indicated at 15 in Fig. 2, the voltage across the horizontal deflecting coils 11 is substantially a rectangular voltage impulse during the return line period. However, the voltage across the vertical deflecting coils 12, while it contains an impulse component, is close enough to a saw-tooth wave so that it may be considered as such for the present purpose. Thus the voltage across coils 12 may be represented as in Fig. 3. While the particular wave shape across a specific deflecting coil is not important so far as the invention is concerned, it may be noted that the reason for the difference in the voltage wave shapes across coils 11 and 12 is that at the high horizontal deflecting frequency the coils 11 have high inductive reactance as compared with their resistance, whereas at the low vertical deflecting frequency the coils 12 have low inductive reactance as compared with their resistance.

The voltages appearing across deflecting coils 11 and 12 are applied through conductors 16 and 17 to the input circuits of amplifier tubes 18 and 19, respectively, which have a common plate circuit connected to the control electrode 3 for supplying blanking impulses thereto during normal operation and for supplying a high protective bias in the event of failure of either the horizontal or vertical deflection.

First, considering the impulses taken from the horizontal deflecting coils 11, they are impressed across a voltage divider resistor 21 through a coupling condenser 22. Voltage impulses from divider 21 are impressed through a grid condenser 23 and a conductor 24 across the grid 26 and the cathode 27 of the tube 18. It will be noted that 40 the cathode is held at A-C. ground potential by a bypass condenser 25.

A grid leak resistor 28 is provided which has sufficiently high resistance with respect to the grid condenser 23 to provide grid leak bias on the tube 18 due to the positive voltage impulses from the deflecting coils 11 driving the grid 26 positive periodically.

The plate 29 of the tube 18 is supplied with an operating voltage through a plate resistor 30, 50 the voltage being taken from a potentiometer resistor 31 connected across a portion of the voltage divider 32 of the power supply unit. Potentiometer 31 is provided with bypass condensers 33 and 34.

The voltage drops across plate resistor 30 and

across the right-hand portion of potentiometer 31 are applied through conductors 36 and 37 to the control electrode 3 of the cathode ray tube as a biasing potential.

Thus it will be seen that each voltage impulse applied to the grid of tube 18 causes a negative impulse to be applied to the control electrode 3, this negative impulse being of sufficient amplitude to block the cathode ray during the return line period. It will also be seen that in the event of failure of the horizontal deflection the negative bias on the grid 18 is reduced (becomes zero in the circuit shown) whereby the plate current through resistor 30 increases to apply a high negative bias to control electrode 3, this high bias being great enough either to block the cathode ray or to so reduce its intensity that it will not injure the mosaic screen 7 when it is stationary thereon or when it is being deflected in one direction only.

It will be understood that the above-mentioned grid leak biasing is obtained due to grid current charging condenser 23 each time the grid 26 is driven positive by a voltage impulse. At the end of each charge, the condenser 23 partially discharges through the grid leak resistor 28, the time constant being such that this discharge between successive incoming impulses is small whereby the biasing voltage is substantially a constant value.

Figure 5 illustrates the operation of the amplifier tube 18. The voltage impulses, having the A-C axis indicated, are applied to the tube with sufficiently low amplitude to cause the greater part of each impulse to appear in the plate circuit. It will be noted that peaks of impulses 15 drive the grid positive to provide the bias indicated on the drawings. The impulses appearing in the plate circuit of tube 18 preferably have several times the amplitude necessary for driving the cathode ray tube 1 beyond cut-off. Thus the impulses 15 are effective for blanking the cathode ray for a period determined by the width of the impulses at a point a considerable distance down from the top of each impulse as indicated by the dotted lines in Fig. 2.

In its preferred form, the invention is applied to the vertical deflecting circuit as well as to the horizontal deflecting circuit. As shown in the drawings, the voltage from across deflecting coils 12 is applied through the conductor 17 across what may be referred to as a differentiating circuit, this circuit comprising a condenser 41 and a resistor 42 in series. By choosing proper values, the voltage appearing across the resistor 42 may be given substantially an impulse wave form as shown at 48 in Fig. 4. This voltage is impressed across the grid 43 and cathode 44 of the tube 19 through a grid condenser 46 and through a connection which may be traced through ground, the bypass condenser 25 and a conductor 47 to the cathode 44.

In order to provide grid leak biasing for the tube 19, a grid leak resistor 48 is given high enough resistance to prevent the charge on the condenser 46 from leaking off too fast between successive voltage impulses. This action is the same as described in connection with the biasing of the tube 18.

If desired, a series of resistor 49 and a shunt condenser 51 may be provided in order to reduce the possibility of horizontal cross talk from affecting the operation of the tube 19. The resistor 49 also helps to flatten off the peaks of the

impulses shown in Fig. 4 to make them more suitable for blanking.

The plate 52 of the tube 19 is supplied with an operating voltage through the plate resistor 30 whereby the plate current of this tube as well as that of tube 18 flows therethrough. Thus, a decrease in bias on the grid of either tube 18 or 19 will increase the negative bias on the control electrode 3.

The wave-shaping elements 41 and 42 are given the proper values to put a vertical blanking impulse on the cathode ray tube of the proper width or duration to block the cathode ray during the vertical return line period. If the deflecting circuit design is such that the voltage across coils 12 is substantially an impulse, the differentiating circuit 41-42 is unnecessary.

In the example illustrated, the vertical blanking impulses 49 are of sufficient amplitude to drive the cathode ray tube 1 beyond cut-off a substantial amount, whereby the effective blanking width of these impulses is that indicated by the dotted lines in Fig. 4.

It will be apparent that in the circuit illustrated the adjustment is such that, when the cathode ray is being deflected in both directions, a normal small operating bias is applied to the control electrode 3, the current through resistor 30 being small at this time. In the event of failure of either deflecting circuit, the bias on an amplifier tube is removed and the current flow through the plate resistor 30 increases sufficiently to block the cathode ray. Also, during normal operation, the impulses shown in Figs. 2 and 4 are applied to the control electrode 3 with sufficient amplitude to block the cathode ray during the return line periods.

On the drawings, the values of certain resistors and condensers have been indicated in ohms, megohms and microfarads, merely by way of example.

From the foregoing, it will be seen that I have provided an improved circuit for protecting a cathode ray tube as well as a simple circuit which functions both for blanking the cathode ray and for giving the desired protection.

I claim as my invention:

1. The combination of cathode ray producing means having a control electrode for controlling the intensity of said ray, a deflecting device for deflecting said ray, a deflecting circuit means for applying a periodic deflecting voltage across said deflecting device for deflecting said ray, and means controlled by said periodic voltage both for blocking said cathode ray during the return line period and for applying a substantially steady negative biasing voltage to said control electrode of sufficient amplitude to substantially reduce the intensity of said ray in response to failure of said deflecting circuit means.

2. The combination of cathode ray producing means having a control electrode for controlling the intensity of said ray, a deflecting device for deflecting said ray, a deflecting circuit for applying a periodic deflecting voltage across said deflecting device for deflecting said ray, an amplifier tube having a cathode, a control grid and a plate, means for applying said periodic voltage across said cathode and control grid through a grid condenser with said voltage being of positive polarity at the control grid, a grid leak resistor connected between said cathode and said control grid, said grid condenser and said grid leak resistor having such relative values a substantial steady biasing voltage is applied to said

control grid due to a grid leak biasing action, means for applying an operating voltage to said plate through a plate resistor, and means for connecting the control electrode and cathode of said cathode ray tube across said plate resistor through direct current connections whereby blanking impulses are applied to said control electrode through said tube and whereby an increased negative voltage is applied to said control electrode to reduce the intensity of the cathode ray in response to failure of said deflecting circuit.

3. Cathode ray tube apparatus comprising a cathode ray tube including means for producing a cathode ray and having a control electrode for controlling the intensity of said ray, horizontal and vertical deflecting devices for deflecting said ray, horizontal and vertical deflecting circuits for applying periodic deflecting voltages across said horizontal and vertical deflecting devices, respectively, for deflecting said ray to scan a rectangular pattern, a pair of amplifier tubes each having a cathode, a control grid and a plate, means for applying one of said periodic voltages across the cathode and control grid of one of said tubes through a grid condenser with said voltage being of positive polarity at the control grid, means for applying the other of said periodic voltages across the cathode and control grid of the other of said amplifier tubes through a second grid condenser with the voltage of positive polarity at the control grid, each of said amplifier tubes having a grid leak resistor connected between its cathode and its control grid, the grid condenser and the grid leak resistor for each of said tubes having such relative values that a substantial steady biasing voltage is applied to the control grid due to a grid leak biasing action, means for applying an operating voltage to the plate of each amplifier 40

tube through a common plate resistor, and means for connecting the control electrode and cathode of said cathode ray tube across said plate resistor through direct current connections 5 whereby blanking impulses are applied to said control electrode through said tube and whereby an increased negative voltage is applied to said control electrode to reduce the intensity of the cathode ray in response to failure of either 10 of said deflecting circuits.

4. The combination of cathode ray producing means having a control electrode for controlling the intensity of said ray, a deflecting device for deflecting said ray, deflecting circuit means for applying a periodic deflecting voltage across said deflecting device whereby there is produced a deflecting field having a useful deflecting portion and a return line portion, an amplifier tube having a control grid and having an input circuit which includes said grid, said amplifier tube having a plate circuit which includes a plate resistor, means for obtaining blanking pulses from said deflecting circuit and for applying them to said input circuit, each of said blanking pulses having a duration approximately equal to the 20 duration of said return line portion and having sufficient amplitude to pass through said amplifier tube, means for generating a negative biasing voltage for said grid in response to the 25 application of said blanking pulses to said input circuit, and means for connecting the control electrode and the cathode of said cathode ray tube across said plate resistor through direct current connections whereby blanking impulses 30 are applied to said control electrode through said tube and whereby an increased negative voltage is applied to said control electrode to reduce the intensity of the cathode ray in response to failure of said deflecting circuit.
